6 Claims. (Cl. 200—110)

This invention relates to a dynamic relay. It is known to construct relays in such a manner that their operation is brought about by the motion of a coil disposed between the poles of a magnet and rotatable about an axis positioned outside the center of the coil or entirely outside the coil. This arrangement is open to the objection that the adjustment of the relay depends upon the position thereof and that the relay to a considerable extent is subjected to shocks and impulses. Furthermore, the natural vibration of the moved part is usually too slow.

The present invention eliminates these drawbacks by providing a relay comprising a magnet 15 and a movable coil secured to a movable part supported at or near its center of gravity. The movable part need not be disposed in a mechanically highly sensitive pivot, but may be arranged on leaf springs, whereby at the same time the period of natural vibration is shortened in a very simple manner.

By way of example, the present invention is illustrated in the accompanying drawing, in which Figures 1, 2 and 3 are diagrammatic views, partly 25 in section, of three different embodiments of the invention.

As shown in Fig. 1, 1 is a permanent steel magnet of the type used in loudspeakers. In the annular gap between the two poles of the magnet 1 a coil 2 is provided which is secured to a frame 4, made for instance of aluminum sheet metal, which is partly recessed and covered by an insulating disk 11. The frame 4 is rockingly supported by the leaf springs 13 only one of which 35 is shown and which may serve for supplying current to the coil 2, in which case they are insulated and attached to the plate 3 and connected to a plug contact 10. The insulating disc 11 supports leaf springs 14 carrying the contacts 6. The springs 14 may be made for instance of thin strips of bronze. When current passes 40 through the coil 2, the entire system supported by the leaf spring 13 will be moved, so that the contacts 6 can perform the necessary circuit closing operations with respect to the fixed contact screws 7. While the drawing shows only one movable and one fixed contact, several such contacts 6, 7 may be provided side by side in such manner that they can be adjusted from above and are 45 therefore located on the same side of the movable part but on the opposite sides of its fulcrum. The movable member 2, 4, is balanced by the counterweight 8, so that it will not move relative to the relay when the position of the latter is altered. 11 is a leaf spring tending to press

the frame 4 upwardly to the right, the tension of which spring can be varied by means of a screw 9.

Measurements have shown that with such a relay at a current energy of 10^{-7} to 10^{-6} watts 5 contact pressures of sufficient magnitude and corresponding safety in operation can be obtained.

When several contacts 6, 7 are employed and arranged on both sides of the bearing of the frame 4 on the leaf springs 13, a particular advantage can be attained according to the invention by one pair of contacts 6, 7 being adjusted to the right and left somewhat more loosely than the others, the two contacts acting, respectively, as movable and fixed contact. The ends of the coil are then connected with the more loosely adjusted contacts, so that the coil will be short-circuited, as these contacts make connection. If contact is made with such energy that the danger 20 of chattering of the frame arises, after the movable contacts have made connection the more loosely adjusted contacts are also connected and thus the coil 2 is momentarily short-circuited. The currents induced therein momentarily consume the kinetic energy, and frame 4 is not thrown back.

The construction shown in Fig. 2 aims at rapid contact making. The contacts 12, 14, corresponding to the contacts 6, 7 of Fig. 1, are arranged a great distance from the center of the oscillating motion of frame 4, whilst the coil 2 itself makes only very small motions in the gap of the magnet 1. The frame 4 is entirely pressed 30 for instance of insulating hard paper and secured again to the insulating plate 3 by the supporting leaf springs 13. Balancing is effected by the weight 8. The conductors 42 for the contacts 12 are guided near the center of oscillation of the frame 4 and then pass as flexible conductors to the stationary portion of the relay. In case of continuous current actuation the spring 16 like the spring 17 in Fig. 1 acts to return frame 4. Experience has shown that with such relays at 35 an energy rate of a few thousandths of a watt 40 in case of alternating currents up to about 1000 hertz, clean response of the relays can be attained and that at these frequencies the relay 45 on a movable and a fixed contact perfectly performs four operations per oscillation or 4000 50 operations per second. It is advisable to utilize the springiness of the bronze strips 38 supporting the contacts 12 for throwing back the frame after current in the coil 2 ceases. The natural frequency of these bronze strips is so great that 55

it is far beyond 1000 hertz and therefore does not affect the operation of the relay. Preferably, however, the oscillation of the bronze strips is further damped by means of rubber buffers 48, as 5 indicated in Fig. 3.

According to the present invention, these relays are further so constructed that the magnet can be separated from the other self-contained structure. For example, Fig. 2 indicates that the magnet 10 can be separated from the system by the loosening of the screws 15. This affords the advantage that the magnet can be magnetized separately and the danger of dust, particularly iron filings, entering the gap during the mounting is 15 eliminated. The gap and the whole upper portion of the relay are closed dusttight by a paper tube 36 shown in Fig. 2 while the cap 47 closes only the upper portion down to the plate 3. In this way the cap is not loaded with the great 20 weight of the magnet which may serve as a convenient handle for manipulating the relay, and the connections, such as the plug pins 10 in Fig. 1, can freely extend outwardly.

According to Fig. 3, the invention further provides that the actuating current flows parallel 25 or in series with the coil of an electromagnet 25. The contact 49 with the countercontact 31 is attached to a straight leaf spring 24 and the contact 50 with the countercontact 30 to the bent 30 leaf spring 28 which, owing to initial tension, compresses the rubber buffer 48. The frame 23 is supported by the leaf springs 13. The counter-contacts 30 and 31 are disposed in the cap or 35 casing 32 covering the entire relay. The conductors of the contacts lead to the plug plate 51. The armature 26 of the electromagnet 25 is secured to frame 23, and the dimensions are chosen so that at the moment contact is made the distance of the electromagnet from its armature 40 becomes very small. It is known that the pull between magnet and armature increases considerably with the decrease in distance, so that the initial motion of frame 23 is effected almost exclusively by the pull of the coil 2 whilst 45 towards the end of the motion the effect of the electromagnet makes itself more and more felt and finally expresses itself in a considerable increase of contact pressure. The armature 26 serves also for balancing frame 23. The principal 50 magnet 22 is in this case also an electromagnet which is energized by a separate source of current.

It is further possible to provide several windings in the coil 2, two of them, 20 and 21, being shown in the drawing, thereby to produce a 55 differential action. For example, the coil 21 may constitute the operating coil of the relay, and the coil 22 (Fig. 2) may be connected with the short-circuiting contacts 61, 62 and 60, 63. In that event, the same damping action of the 60 frame 4 is attained, as when the operating coil itself is short-circuited by one of these contacts, although in a somewhat lesser degree. In this case, however, there is the advantage, that the intensity of the current in the short-circuiting

conductors can not excessively increase, in case the outer resistance of the circuit comprising the current generator is slight. Instead of short-circuit a balanced damping can of course be attained by the insertion of an outer resistance. 5

Fig. 3 further shows the retarding device for 10 retarding in an adjustable manner the making and breaking of contact. It is known to employ as brake for the movable parts of a relay an air piston which tightly moves in an airtight cylinder. The form of relay shown does not require a special piston and air cylinder, the body of the 15 coil 2 being simply closed on top, for instance by a paper sheet 33. The core of the magnet then acts as stationary piston and the body of the coil as a movable cylinder. To regulate the retardation air is admitted through the bores 37 and 40 which can be closed more or less by the screw 35.

I claim:

1. A dynamic relay, comprising a casing, a magnet having between its poles an annular gap, a coil extending into said gap, a frame outside of said magnet supporting said coil and forming together therewith a movable member, resilient 25 means supporting said movable member, cooperating contacts on said frame and said casing, and means for so balancing said frame that its position relative to the contacts on the casing is varied only upon said coil being acted upon by 30 electromagnetic forces, but is not varied by mechanical forces acting on said casing.

2. The combination as specified in claim 1, including additional contacts for short-circuiting said coil after completion of the operation of 35 the relay.

3. The combination as specified in claim 1, including an auxiliary winding connected with said coil, and additional contacts for short-circuiting said coil after completion of the operation of the relay.

4. The combination as specified in claim 1, in which all the contacts are positioned on one side of said frame.

5. The combination as specified in claim 1, including an iron armature provided on said frame, an iron core connected with said casing, and an electromagnetic coil on said iron core being electrically connected with said first-mentioned coil and receiving the operating current. 50

6. A dynamic relay, comprising a casing, a magnet having between its poles an annular gap, a coil extending into said gap, a frame outside of said magnet supporting said coil and forming together therewith a movable member, a leaf 55 spring supporting said movable member, cooperating contacts on said frame and said casing, and means for so balancing said frame that its position relative to the contacts on the casing is varied only upon said coil being acted upon by 60 electromagnetic forces, but is not varied by mechanical forces acting on said casing.

ERNST BRÄUER.
